US00D770311S

(12) **United States Design Patent** (10) **Patent No.:** **US D770,311 S**
(45) **Date of Patent:** **** Nov. 1, 2016**

(54) **TIMER**

(71) Applicant: **Orbit Irrigation Products, Inc.**, North Salt Lake, UT (US)

(72) Inventors: **Kent C. Ericksen**, Centerville, UT (US); **Stuart Eyring**, Bountiful, UT (US); **Karl L. Connolly**, Bountiful, UT (US); **Jeffrey C. Thurgood**, Severance, CO (US); **Alan T. Ence**, Fruit Heights, UT (US)

(73) Assignee: **Orbit Irrigation Products, Inc.**, North Salt Lake, UT (US)

(**) Term: **15 Years**

(21) Appl. No.: **29/532,141**

(22) Filed: **Jul. 1, 2015**

Related U.S. Application Data

(60) Continuation of application No. 29/500,449, filed on Aug. 25, 2014, now Pat. No. Des. 736,104, which is a division of application No. 29/450,680, filed on Mar. 20, 2013, now Pat. No. Des. 713,271.

(57) **CLAIM**

The ornamental design for a timer, as shown and described.

DESCRIPTION

FIG. 1 is an elevated perspective view of a timer according to our new design;

FIG. 2 is a front view of the timer shown in FIG. 1;
FIG. 3 is a rear view of the timer shown in FIG. 1;
FIG. 4 is a top view of the timer shown in FIG. 1;
FIG. 5 is a bottom view of the timer shown in FIG. 1;
FIG. 6 is a first side view of the timer shown in FIG. 1; and,
FIG. 7 is a second side view of the timer shown in FIG. 1. The portions of the timer shown in broken lines form no part of the claimed design. Any empty region surrounded by broken lines is also unclaimed, inclusive of the broken line itself.

1 Claim, 7 Drawing Sheets
